UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

CURRENT-REGULATING PLUG AND PULL- SOCKET.

1,335,017.

Specification of Letters Patent. Patented Mar. 30, 1920.

Application filed August 15, 1919. Serial No. 317,825.

To all whom it may concern:

Be it known that I, ANTONIO PAPINI, a subject of the King of Italy, having resided in the United States one year last past and 5 having declared my intention of becoming a citizen thereof, residing in the city and county of Philadelphia, State of Pennsylvania, have invented a new and useful Current-Regulating Plug and Pull-Socket, of 10 which the following is a specification.

My invention relates in general to electric regulators or rheostats, for use in connection with electric circuits designed both for lighting purposes and in connection with 15 medical batteries or other devices, including dynamos and motors, to which electrical current is supplied and caused to pass through a resistance material such, for instance, as powdered carbon, or a composite 20 resistance material composed of carbon as a conductor and of mineral wool or spun glass both comminuted or reduced to powder and mixed together and then commingled with the carbon, so as to form a 25 more or less elastic material adapted to be compressed to increase its conductivity, or loosened to increase its resistance, in order to increase or diminish the force or strength 30 of the current passed through it, so as to regulate the brilliancy of the light or the potency of the battery or device to which the current is applied.

The object of my invention is the construction of a regulator in which the control 35 of the resistance material, of whatever character it may be, by the movement of a piston carrying the lower contact point and controlled to up and down movement to bring its contact point up to or away from 40 the upper contact point by the employment, broadly expressed, of a threaded piston rod actuated to rotate by the action of a rotary wheel operated from the exterior of the casing, and in which the means employed 45 for effecting such rotation extend exteriorly of the casing and are adapted to be manually operated.

With the foregoing object in view my invention comprehends means for introducing

conductors into the outer shell of the device and for retaining them in introduced position by supporting and retaining means hereinafter described.

My invention further consists in a special mounting of the piston rod relatively to the 55 lower contact point, and means for occasioning the control movement of said piston rod and contact point.

Other features of my invention are illustrated in the drawings and hereinafter described.

For the purpose of illustrating my invention, I have shown in the accompanying drawings one form thereof which is at present preferred by me, since the same will be 65 found in practice to give satisfactory and reliable results, although it is to be understood that the various instrumentalities of which my invention consists can be variously arranged and organized and that my 70 invention is not limited to the precise arrangement and organization of these instrumentalities as herein shown and described.

In the drawings,

Fig. 1 represents a central, vertical, sectional elevation of a regulator embodying my invention;

Fig. 2 represents a side elevation of a hollow spring nut adapted to close the upper 80 orifice of the outer shell of the casing of the regulator and to confine within it against displacement the electrical conductors which are contained within said outer shell;

Fig. 3 represents a fragmentary, central, sectional elevation, through a modified form of my inner casing, illustrating as applied to it and as the equivalent of the outer shell of the construction of Fig. 1, a threaded 90 plug cap by means of which the regulator may be applied to any desired socket for carrying it;

Fig. 4 represents a central, vertical, sectional elevation of a modified form of shell 95 or casing and means for retaining in divided relationship the resistance material;

Fig. 5 represents a central, vertical section

of an apertured block of resistance material; and

Fig. 6 represents a fragmentary plan of a basal flange of the inner casing, indicating a radial channel through which a conductor passes.

Similar numerals of reference indicate corresponding parts in the figures.

Referring to the drawings:—

- 10 1 designates an inner cylindric casing formed with a basal flange 2, and secured within an outer shell 3, preferably made in two parts, an upper part to which the number 3 is applied, and a lower part 5, which 15 are conveniently connected by screws 6. Through the lower shell 5 screws 7 pass into the basal flange 2 of the inner casing 1 to support the latter concentrically within the regulator considered as an entirety.
- 20 8 designates a screw head upon the upper end of a screw which forms the upper contact point 9, and passes centrally through the cover portion of the inner casing 1. Under its head the screw confines one of the 25 conductors 14 against an upper brass washer 11, while a lower brass washer 12 beneath the cover portion is retained by a nut 10 threaded upon the externally threaded portion of the screw forming the upper contact 30 point 9. The conductors 13 and 14 which pass through the spring nut are preferably wrapped with respect to each other, and the conductor 14 curves downward to an electrical union with a socket 15, which in the 35 use of the regulator with an electrical lighting system, possesses the form of a threaded head of a light bulb, not illustrated, into which the head is screwed.

In its passage downward from the upper 40 portion of the casing, this conductor 14 passes through a radial channel 35, formed either, as shown in Fig. 6, in the basal flange 2 of the inner casing 1, and through some corresponding channel in a cup basket 4 disposed within the lower part of the outer shell 5 and resting upon ledges with which said shell is formed, as shown in Fig. 1.

Between the cup basket 4 and the socket 15 below said cup basket, and between said 50 socket 15 and the lower drawn-in end of the outer shell 5 is an insulating shell 16, which completes the assemblage of elements of the casing below the cup basket.

17 designates a resistance material of any 55 preferred character, for instance, a mixture of graphite and mica or other conductor, which is disposed within the hollow interior of the inner casing 1, and the mass of which rests upon a piston preferably formed of 60 two metal heads 18 comprising between them a filling 19 of the character, for instance, of an asbestos packing, which is held in place between said piston heads 18 by the compression of nuts 21 on an externally threaded 65 hollow piston rod 22, which extends com-

pletely up to above the upper of the two piston heads, and upon which intermediately of its length is fixedly mounted a brass nut or boxing 30, which is fast to a rotary operating chain-wheel 29 peripherally grooved 70 as at 31 to receive a wheel chain 32 which passes out through the walls of the outer shell and is manually operated from the exterior of the shell as a whole, to effect the desired rotation of the wheel. 75

The piston rod 22 at its upper end and internally and axially of it, is provided with a piston rod pin 23, forming the lower contact point 20, which passes through a collar 24 on the base of the cup basket 4, and 80 downwardly through said base so as to receive and, by the action of a nut 25, clamp the spring contact 26 in place against the cup basket.

27 designates a hollow, cylindric insulating bushing on the piston rod pin 23, and 85 28 designates a hollow, cylindric metal bushing bearing against the hollow interior of the piston rod 22.

The foregoing arrangement is one of more 90 or less detail, to permit of the rotation and consequent raising and lowering of the hollow piston rod 22 under the influence of the wheel 29, through the brass nut 30 fixed to said wheel and operating to raise and lower 95 the piston rod and lower contact point 20, to effect and to maintain a regulated electric connection between said lower contact point 20 and the upper contact point 9.

The return stroke of the piston is limited 100 by the contact face 36 on the base of the piston rod 22, and the contact face 37 which conveniently rests upon the collar 24 upon the base of the cup basket 4.

In the detail illustrated in Fig. 1, the 105 externally threaded piston rod 20 extends axially lengthwise of both the inner casing 1 and the cup basket 4 and being fastened permanently to the piston 18, 19, by the nuts 21, as already explained, is, of course, compelled to move upward or downward because its external threads are engaged with the internal threads of the brass nut 30, which, as explained, is fast to the insulated operating wheel 29. 110

As a convenient connection for the mounting of the parts, the piston rod pin 23 referred to as locked to the base of the cup basket, as already explained, passes up through a hollow, cylindric insulating bushing 27, between and surrounding which and extending to fill the hollow, smooth interior of the piston rod 22, is a cylindric, metal bushing 28 which extends up almost to the internal bottom 44, so to speak, of the piston 125 rod and is there surmounted by an insulated bushing 40. By this means, electrical connection both with the internal bottom 44 of the piston rod, the metal pin 23 and the brass bushing 28 is in part effected, a 130

threaded brass bushing 41 between the pin 23 and the bushing 28, completing the connection.

In Fig. 4, I have represented a modified form of inner casing in which the resistance material 17 is compacted into the form of apertured disks or fibrous washers of resistance material such as asbestos mixed with graphite, one of which is shown detached in Fig. 5, and a plurality of which are embraced within the hollow interior of the casing.

To permit of the venting of the heat created when the resistance material is intensely compressed, a circular hollow metallic box 39, Fig. 4, perforated by external perforations 42 which register with radial outlets 43 in the walls of the casing to permit of the escape of the heat, is employed.

In Fig. 5, one of these disks of resistance material is, as explained, illustrated as taken out from the casing.

It will now be apparent that I have devised a novel and useful construction of a current regulating plug and pull socket which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a device of the character stated, a receptacle containing a resistance material and a compressing device for varying the pressure upon said material, said device embodying a piston, a hollow externally threaded piston rod, and a rotary operating wheel internally threaded upon the piston rod to cause the elevation or depression of said piston rod and its piston in the rotation of the wheel, and means for controlling the movement of said wheel.

2. In a device of the character stated, a receptacle containing a fixed and a movable contact point, a resistance material, and a compressing device for varying the pressure upon said material, said device embodying a piston, a hollow, externally threaded piston rod, a rotary operating wheel internally threaded upon the piston rod to cause the elevation or depression of said piston rod and its piston in the rotation of the wheel, and means for controlling the movement of said wheel.

3. In a device of the class recited, an inner closing shell or outer casing, a resistance ma-

terial within said casing, and means for varying the pressure upon it, a cup basket below the inner casing, a rotary wheel disposed between said casing and said cup basket and operative upon the pressure varying means to raise and lower said means and means for controlling the movement of said operating wheel.

4. In a device of the character described, an outer shell the upper aperture of which is closed by a spring nut, a receptacle containing a fixed and a movable contact point, a resistance material, a compressing device for varying the pressure upon said material, which device comprises a piston, a piston rod, a wheel operative from the exterior of the casing to elevate or depress the piston rod and piston, and electric conductors entering the outer shell through the spring nut, the terminals of which conductors are respectively connected with the fixed and the movable contact points to complete the circuit.

5. In a current regulating plug and tool socket, the following elements in combination:—an outer shell, an inner casing, a cup basket, piston within said inner casing, a vertically movable piston rod extending into both the casing and the cup basket, an operating wheel for occasioning the vertical movement of said piston rod in either direction, means for occasioning the rotation of said wheel, a fixed contact point within the inner casing, a contact point movable with the piston, electric connections between said contact points, a socket within the outer shell, and a spring contact within said socket for effecting electrical connection with a lamp or other device to which the regulator is to be applied.

6. A current-regulating plug and tool socket, which comprises an external shell, an internal casing formed with a radially extending basal flange connected with the external shell, a cup basket or base below said internal casing and supported by the external shell, an operating wheel supported for rotation between said internal casing and said cup basket and formed with an internally threaded axial aperture, a piston within the internal casing externally threaded to pass through the threaded aperture of the wheel, means for operating the wheel from the exterior of the device, a resistance material in the internal casing, a contact point fixed within said internal casing, a contact point upon the piston, electrical connections between said contact points, and means for connecting the device as an entirety with a carrying support and also with a lamp or device to be operated by it.

7. In a device of the character stated, in combination with an internal casing containing a resistance material and means for effecting the compression of said material,

embodying a piston, a hollow externally threaded piston rod, and a rotary operating wheel internally threaded upon the piston rod to cause the elevation or depression of said piston rod and its piston in the rotation of the wheel, means for controlling the movement of said wheel, and an external shell or casing adapted to fit within and be connected with a support for the device as an entirety.
